UNITED STATES PATENT OFFICE

CHARLES F. PAUL, OF ST. LOUIS, MISSOURI

SASH TRIMMING MACHINE

Application filed October 10, 1930. Serial No. 487,791.

This invention relates to improvements in sash trimming machines, and more particularly to that class of machines employed for trimming or cutting off the ends of pieces of sash or equivalent millwork, at various angles, to cause the resultant end faces to conform to and match, for example, a preformed ornamental face or end of a given length of material.

An object of the present invention is to provide an improved sash trimming machine employing a rotary cutter element which is pre-shaped to conform to the quirks of the material to be processed.

A further object is to provide an improved coper or sash trimming machine including a rotary cutter element which in operation is led across the end portion of the piece to be cut.

A still further object is to provide an improved coper which is simple and easily operated, and which produces a finished product with end copes on the sticking, which correspond to the quirked face of the sticking, and which accomplishes this cutting without any danger of splitting or breaking the piece, or destroying any of the end fibers of the wood as is sometimes the case with the older prevailing types of sash trimming machines in which a knife is forced downwardly through the end fibers of the wood and therefore is very apt to fracture and possibly displace, undesirably, the weaker fibers of the sticking.

Further objects and advantages will appear from the following detailed description of parts and the accompanying drawings, in which:

Fig. 1 is a front elevation of a preferred form of wood coper to which the present improvements are applied; Fig. 2 is a side elevation, partially in section, of the improved device; Fig. 3 is a plan view of a preferred form of cutter element; Fig. 4 is a sectional elevation taken along the line 4—4 in Fig. 3; Fig. 5 is a fragmentary plan view of a portion of the device as viewed from line 5—5 in Fig. 2; and Fig. 6 is a sectional elevation taken along the line 6—6 in Fig. 5.

It will, of course, be understood that the present detailed description of parts and the

accompanying drawings relate to a single preferred executional embodiment of the invention and that substantial changes may be made in the described arrangement and construction of parts without departing from the spirit and full intended scope of the invention.

Referring by numerals to the drawings, 10 represents a support or standard for the operative elements of the machine hereinafter described. A plate 11 is preferably detachably secured to the standard 10, and is, by preference, provided with a plurality of arcuate slots 12 through which extend clamping bolts 13 for independently adjustably positioning tables 14. It will be readily seen that the tables 14 extend radially inwardly along the face of the plate 11, and that their inner ends 15 are pivotally positioned to the vertical plate 11, the pivots being substantially spaced from each other for a purpose herein-after appearing. Each table may be independently adjusted and clamped to the plate 11 at any desired angular inclination in respect to the horizontal, for a purpose herein-after appearing. Bed plates 16 are adjustably and removably secured to the tables 14 by means of bolts 33. These plates are, by preference, formed of a hard wood, and are provided with grooved or quirked portions 18 to correspond to the quirked molding of the particular sticking to be processed, in order to insure a rigid and level foundation or base for the sticking to be placed thereupon during the cutting operation, as will hereinafter appear. The bed plates 16 are made interchangeable so that a bed plate may be provided to conform to the quirked portion of any desired sticking which may be placed on either of the tables.

A vertically movable head 17 is provided, which is guided to provide a straight line sliding movement, by means of suitable channeled or guide surfaces (not shown) formed on the plate 11. A control treadle or foot lever 19 is pivotally attached to the lower portion of the support 10, by means of a pin 20. Intermediate the ends of the lever 19, is provided a pivoted connecting link 21, the other end of which is pivotally secured to the mov-

able head 17. It will be readily seen that the downward movement of the lever 19, produces a downward movement of the head 17, the movement of which will be determined by the 5 guide channels above referred to. A spring 22 is adjustably attached at one or its upper end to a stationary portion of the member 11, and at its opposite end to an intermediate portion of the lever 19. It will be readily 10 seen that the spring will return the head 17 and lever 19 to an upper, normally inoperative position, after releasing the treadle of manual or foot pressure.

A power unit such as an electric motor 23 15 is, by preference, attached to the head portion 17 as by suspension from a bracket or support 34, and hence is movable with the head portion under influence of the lever 19. The motor is, by preference, of a high speed, 20 reversible type for reasons hereinafter appearing, and includes an extended rotor shaft 24 upon which is removably secured a rotary cutter element 25. This cutter may be formed in any desired manner. For instance, as 25 shown in the preferred arrangement in Fig. 3, it may be provided with four cutter blades 26, but it will be understood that a cutter having any other number of blades, may be used. Each blade is, by preference, formed 30 with opposed cutting edges 27, each of which is preshaped to conform to the quirks desired to be cut in the end of the sticking. By preference, the blades are each provided with a flat portion 28 in order to insure sufficient 35 clearance between the cutter and the piece to be cut, as the motor and cutter are brought downwardly by manipulation of the treadle 19.

It will be readily seen that the bed plates 40 extend inwardly, one from each side of the machine, and that a piece of sash or sticking, placed in, say the right hand bed plate as viewed in Fig. 1, extends inwardly into the path of the cutter sufficiently to permit the 45 end of the sticking to be cut. An adjustable stop 29 provided on the bed plate, determines the proper distance placement of the sticking along the bed plate. The use of a stop or equivalent limiting projection such as 29, 50 finds a purpose in cases where the rotary cutter is employed to form only a portion of the end face of the sticking, there being a remaining plane end face portion which may have been precut by sawing according to any usual 55 method. In such a case the desired space relations between such a plane end surface, and the quirks of the remaining end surface, are preserved so that a processed portion, or portions, will engage snugly and uniformly, 60 the mating surfaces.

A starting switch 30 for the motor may be secured to the plate 11, and is provided with a switch lever 31 which by preference is biased by a spring (not shown), to switch- 65 closing position. A projecting member 32

is provided on the movable head 17, and when the head is in its uppermost position, this member holds the switch lever in its open-circuit position. When, however, the head is moved downwardly, due to pressure on the 70 treadle 19, the member 32 moves away from the switch lever, which thus closes the motor circuit, and the motor is started. Again on its upward movement, after pressure is released on the treadle, the projecting member 75 positively engages the lever 31, to open the switch and stop the motor.

As above noted, the motor 23 is, by preference, of a reversible type. By this provision the stickings to be processed, may be 80 placed in either bed plate from either side. For example, when the material is extended from the right side of the device, as viewed in Fig. 1, the motor will rotate clockwise; but when cutting a sticking introduced from the 85 left hand side of the machine and disposed on the corresponding bed plate, the motor may be reversed and rotated in a counter-clockwise direction. By this provision, the 90 rotating knife in its downward travel will 95 always tend to force the sticking into closer contact with the bed plate and to maintain it in close engagement with the stop 29.

The presently preferred electrically operated coper is simple and entirely automatic 95 in its operation, except for the operator's control movement of the treadle to lead the rotary cutter across the end grain of the wood. The finished product is clean cut and free 100 of any chipping off of the under grain of the wood. Also, in older prevailing types of machines, in which a chopping action takes 105 place, as distinguished from a rotary cutting action, there is a tendency for the lower fibers of the wood to break or chip off, which often is so destructive as to render the piece 110 of wood useless for its intended purpose. Since sticking for sash purposes, molding and various uses as trim, is generally cut to exact 115 length, destruction of one end portion destroys the usefulness of the entire piece. If only one end of the sticking has been unsuccessfully processed by the older methods, as often occurs, one or more repeat operations 120 are necessary, resulting in an obvious waste 115 of time and material. With the present improved device, there is no tendency for cracking, breaking, fracturing or splintering off to occur, and hence quantity of production and quality of the finished product are greatly enhanced.

A distinct advantage of the coping device presently described, is found in the facilities afforded for processing comparatively large pieces of material. For example, no difficulty 125 is experienced in forming material considerably greater than two inches in thickness, whereas with the older types of device available for this purpose, it is practically impossible to process sticking of a thickness in ex- 130

cess of one and one-half or two inches. Even where work of this order is attempted with the older devices, a great percentage of material is rejected by reason of breakage and splitting, as above described.

For the sake of providing a complete description, a device has been described as constructed according to present preference, and designed for use in connection with sash 10 sticking. It will, however, be obvious that the device may be employed with or without detailed structural modification, to handle coping work in connection with molding and other wood trim of any of the usual varieties.

15 It will appear that the machine of the present description is semi-portable, light, compact, and consists of a minimum number of working parts, as well as being of rugged construction and requiring no high degree of 20 skill for its successful operation, in fulfillment of the several objects set forth above.

I claim as my invention:

1. In a sash coper, a motor including a 25 rotor shaft, a cutter element connected to said shaft, and provided with radially and axially spaced cutting faces, a plate element adapted to form a bed for sash to be operated upon, means for moving one of said elements transverse to the other to cut the sash, and 30 means for selectively tilting said plate element, while maintaining it in substantial parallelism with the cutter axis.

2. In a sash trimming machine, the combination of a bed plate, an electric motor including a rotor shaft, a cutter rotated by said shaft, and provided with axially spaced, stepped cutting faces, said bed plate being adapted to position a piece of sash endwise to said cutter, and means for leading said 40 rotary cutter across the end of said sash.

3. In an electrically operated coper, the combination of an electric motor having a rotating shaft, a cutter having a quirked face corresponding substantially to the beading to be operated upon, a bed plate for holding the beading, said cutter being rotated by said motor shaft, and means for moving said cutter past said bed plate to cut said beading.

4. In a coping machine, a power unit, a 50 rotary cutting element associated therewith, a support for material in the machine, tiltable about an axis parallel to that of the cutting element, and combined control means for moving said cutting element into working position, and for controlling the energization of said power unit.

5. In a coping machine, an electric motor, a 55 rotary cutter having portions of stepped cutting diameters, and carried by the motor, a support for material in the machine, movable, for adjustment, about an axis parallel to that of said cutter, a control element arranged for moving the motor and support 60 relative to each other and a switch for the

motor, arranged for actuation by said control element.

6. In a device for producing a finished ornamental end face on wood sticking or the like, a rotary cutter, a power unit associated 70 therewith, means for leading said cutter across the end of the sticking, said cutter having edge portions, adapted to form, simultaneously, a plurality of end quirks on the sticking, corresponding substantially to the 75 quirks on a lateral face of such sticking.

7. In a coping machine, an angularly adjustable bed plate for sticking, a motor, and a rotary cutter having a plurality of laterally and radially spaced cutting edges, and in 80 driven relation to said motor.

8. In a coping machine, a bed plate for sticking, a motor, a rotary cutter driven by the motor, and having a plurality of cutting edges spaced along its axis of rotation, means 85 for leading said rotary cutter across the end of said sticking, and means for angularly adjusting the bed plate about an axis parallel to the axis of said cutter.

9. In a coping machine, a base including a 90 hollow vertical standard; a mounting plate carried by said standard and having a curved slot on each side of the standard; a pair of supports adapted for independent angular adjustment with respect to said standard, the 95 supports each being pivoted near its inner end to said mounting plate, with the pivots therefor in substantially spaced relation; means associated with said curved slots, for angularly adjusting said supports; an electric motor; a mounting therefor, slidably disposed with respect to the upper portion of said standard; a foot-operated control member pivoted near the lower portion of said standard, an operating arm extending 100 through a portion of said standard to the support for said motor, a spring having adjustable connection with fixed anchorage near the upper end of said standard, and connected at its lower end with said foot control member, and a rotary cutter carried and arranged for operation by said motor, said cutter having a series of cutting edges spaced lengthwise of each other along the cutter axis,

105 a bed plate detachably carried by each of said angularly adjustable supports, and an end stop for sticking in the machine, associated with the inner end of each of said bed plates.
